FLEXIBLE PISTON FOR INTERNAL-
COMBUSTION ENGINES

Philip S. Webster, Muskegon, Mich.

Application July 15, 1943, Serial No. 494,758

1 Claim. (Cl. 123—78)

The present invention relates to flexible pistons for internal combustion engines and more particularly to an improvement over or modification of the flexible piston illustrated and described in my co-pending application for Letters Patent of the United States of America, Serial No. 435,272, filed March 19, 1942, to issue July 6, 1943, as Patent No. 2,323,742.

The primary objects of the instant invention are to provide a piston for an internal combustion engine of the general character above indicated whereby detonation is controlled; to provide a piston having an auxiliary head which compresses the exhaust gases of the previous cycle into the combustion chamber, causing added turbulence and resulting in a more uniform burning of the compressed mixture of fuel and air; to provide such a piston whose auxiliary head is secured to but flexibly spaced from its lower portion permitting free absorption of excess combustion pressure during periods of ignition and burning after which it returns to normal position and before the exhaust valve releases the expanded gas; to provide such a piston whose auxiliary head retains the exhaust gases during the succeeding intake and compression strokes, thereby acting as a shock absorber and preventing excessive detonation; to provide such a piston, the flexible movement of whose auxiliary head may be varied and initially determined to suit any particular available fuel; to provide such a piston whose auxiliary head is provided with rings, and is concentric with the cylinder walls at all times, thereby providing for uniform heat transfer through its rings without scuffing or "blow-by"; and, to provide such a piston which is reasonably light in weight, highly efficient in use and is reasonably economical in manufacture.

Illustrative embodiments of the invention are shown in the accompanying drawings, wherein:

Figure 1 is a vertical sectional view of the flexible piston on line 1—1 of Figure 2;

Figure 2 is a top plan view of the flexible piston, partly broken away;

Figure 3 is a sectional view thereof on line 3—3 of Figure 2;

Figure 4 is a fragmentary sectional view similar to Figure 3 but showing the auxiliary head of the piston in depressed position;

Figures 5, 6 and 7 show the combustion cycle of the flexible piston within its cylinder; and

Figure 8 diagrammatically illustrates how detonation is prevented and how improved performance results from the use of the flexible piston of this invention.

Referring then to the drawings wherein like parts of the structure shown are each designated by the same numerals in the several views, the vertically flexible or axially expansible-contractible piston there shown generally is preferably of cast aluminum alloy and comprises an upper auxiliary portion or combustion head 10, a lower portion 11 having oppositely disposed wrist pin receiving apertures 12, a central connecting member 13 having oppositely disposed wrist pin slots 14 for securing the upper auxiliary portion 10 to the power portion 11 by means of the wrist pin 100, and a bellows type expansion spring 15 interposed between the upper auxiliary portion 10 of the piston and the lower portion 11 thereof.

The upper auxiliary portion 10 of the piston is provided with a centrally disposed bore 16, downwardly tapered at its upper end and likewise preferably having a tapered steel annular insert 17 and the central connecting member 13 is further provided with a centrally disposed bore 18 in alignment with the bore 16 of the upper auxiliary portion 10. A bolt 19 provided with a tapered head 20 and with a screw threaded shank 21 flexibly secures the upper auxiliary portion 10 of the piston with the central connecting member 13 by means of the nut 22.

The upper auxiliary portion 10 of the piston is provided with conventional compression and oil ring grooves 22, 23, respectively, and with a depending sleeve 24, preferably of steel, within its internal bore. The central connecting member 13 is preferably provided with a plurality of piston ring grooves 25 within which are seated oil rings 26 engaging the inner surface of the depending sleeve 24 and the lower portion of the piston is provided with a compressing ring groove 50.

In securing the several parts of the piston in their assembled relation, the bellows type expansible spring 15 is first slid upwardly around the depending sleeve 24 and the central connecting member 13 is then slid upwardly through the bore of the lower portion 11 of the piston to compress the bellows type spring after which the bolt 19 is inserted through the bores 16, 18 and the nut 22 turned on the shank 21 to secure the upper auxiliary portion 10 of the piston and the central connecting member 13 whereupon the wrist pin 100 is inserted through the apertures 12 and slots 14 permitting the upper auxiliary portion 10 of the piston to axially space itself from the lower portion 11 thereof.

Combustion of the atomized fuel within the cylinder 28 above the auxiliary upper portion of

the piston 10 by means of the spark plug 29 causes the head to travel axially from its position shown in Figure 5 compressing the bellows type spring 15 as shown in Figure 6, whereupon the central connecting member 13 is depressed to its position shown in Figure 7, at which time the lower portion 11 of the piston is caused to be moved and the auxiliary upper portion 10 of the piston is again in spaced relation to the central connecting member. Detonation is thus prevented and relatively higher compression ratios are provided than are provided with conventional type pistons using standard grades of fuel.

Detonation is prevented by the added turbulence of the exhaust gases in the chamber mixing with the combustible mixture of fuel and air as the gas pressure increases to displace the upper auxiliary portion of the piston 10 relative to the lower portion 11. Thus, an engine having an effective compression ratio of ten to one on the exhaust and intake stroke will have the detonation and power characteristics of an engine having a five to one compression ratio, all as indicated in Figure 8 wherein the ordinate indicates pressure, the abscissa indicates volume, the cross-hatching indicating an engine with standard pistons and the dotted lines indicating an engine having flexible pistons of the instant invention.

It will thus be seen that the flexible piston herein shown and described is well adapted to control detonation, that the auxiliary upper portion which compresses the exhaust gases of the previous cycle into the combustion chamber causes added turbulence and a more uniform burning of the compressed mixture of fuel and air, that the auxiliary upper portion of the piston is secured to but flexibly spaced from its lower portion permitting free absorption of excess combustion

pressure during periods of ignition and burning after which it returns to normal position, and before the exhaust valve releases the expanded gas, that the auxiliary upper portion of the piston 5 retains the exhaust gases during the succeeding intake and compression strokes thereby acting as a shock absorber and preventing excessive detonation, that the flexible movement between the several portions of the piston may be varied and initially determined to suit any particular available fuel, that the auxiliary upper portion of the piston is provided with rings and said portion is concentric with the cylinder walls at all times thereby providing for uniform heat transfer through its rings without scuffing or blow-by, and that the flexible piston herein shown and described is reasonably light in weight, highly efficient in use and reasonably economical in manufacture.

While but one specific embodiment of the invention has been herein shown and described, it will be understood that certain details of the construction shown may be altered or omitted without departing from the spirit of the invention as the same is defined by the following claim.

I claim:

A piston for an internal combustion engine having a hollow head portion and a lower portion in spaced relation thereto, the inner wall of the hollow head portion having a close fitting depending sleeve, a connecting member limitedly slidably disposed relative to the lower portion secured to the upper portion thereof and provided with ring grooves having sealing rings therein, and a 30 bellows type expansion spring interposed in the 35 space between the upper and lower portions of the piston.

PHILIP S. WEBSTER.
